(57) **CLAIM**

The ornamental design for a portable performance test stand for scaled radio-controlled nitro cars, as shown and described.

DESCRIPTION

FIG. 1 is a front perspective view showing my new design.

FIG. 2 is a rear perspective thereof.

FIG. 3 is a top plan view thereof.

FIG. 4 is a front elevation view thereof.

FIG. 5 is a bottom plan view thereof.

FIG. 6 is a rear elevation view thereof; and, FIGS. 7 and 8 are left and right end views, respectively, thereof.
